UNITED STATES PATENT OFFICE.

VIRGIL PRICE, OF WOODSIDE, NEW YORK.

DESIGN FOR BUCKLES.

Specification forming part of Design No. **7,959**, dated December 29, 1874; application filed March 27, 1873.
[Term of Patent 14 years.]

To all whom it may concern:

Be it known that I, VIRGIL PRICE, of Woodside, in the county of Queens and State of New York, have invented a new and original Design for a Buckle, of which the following is a specification:

The accompanying drawing represents a face view of my new design for a buckle.

This invention relates to a new base-relief ornamentation formed on cast or sheet metal buckles; and consists in the representation of two angels kneeling at the ends of the ark

and between the handles thereof, their wings extending over the ark, as shown. In the background the rising sun is represented. Suitable scrolls, in imitation of clouds, are at the feet of the angels.

What I claim as new, and desire to secure by Letters Patent, is—

The design for a buckle, as shown.

VIRGIL PRICE.
